B. McGILVRAY

WRENCH

Filed March 29, 1926

*Inventor:
Bernard McGilvray,
by Walter E. Lombard,
Atty.*

UNITED STATES PATENT OFFICE.

BERNARD McGILVRAY, OF QUINCY, MASSACHUSETTS.

WRENCH.

Application filed March 29, 1926. Serial No. 98,069.

This invention relates to wrenches and has for its object the production of a device of this character which may be used either as a monkey wrench or a pipe wrench as desired.

5 This object is attained by the mechanism illustrated in the accompanying drawing.

For the purpose of illustrating the invention, one preferred form thereof is illustrated in the drawings, this form having been 10 found to give satisfactory and reliable results, although it is to be understood that the various instrumentalities of which the invention consists can be variously arranged and organized, and the invention is not limited to the precise arrangement and organization 15 of these instrumentalities as herein shown and described except as required by the scope of the appended claims.

Of the drawings:

20 Figure 1 represents an elevation of a wrench embodying the principles of the present invention and showing the jaws open in position for use as a monkey wrench.

25 Figure 2 represents an elevation of same, partly in section, and showing the jaws closed.

Figure 3 represents a sectional detail showing the auxiliary jaw locked to the 30 fixed jaw in position for use as a monkey wrench.

Figure 4 represents a similar detail showing the auxiliary jaw locked to the movable jaw and in position for use as a pipe wrench, and

35 Figure 5 represents a perspective of a portion of the wrench showing the auxiliary jaw locked to the movable jaw.

Similar characters indicate like parts 40 throughout the several figures of the drawing.

In the drawings, 10 is a fixed jaw of a wrench, said jaw having a serrated working face 11 and a shank 12 extending therefrom.

45 A portion 13 of the shank 12 is flat sided and extends through the movable jaw 14 which is provided with a flat working face 15.

The shank 12 is also provided with an- 50 other reduced flat faced portion 16 on which is mounted the member 17 held in position thereon against the shoulder 18 by means of a set screw 19, the end of which is positioned in the recess 20 in the portion 16.

55 Formed integral with the portions 13, 16

is a cylindrical portion 21 extending through a wooden handle 22 which is retained normally upon the cylindrical portion 21 by means of the headed screw 23.

The flat sided portion 13 of shank 12 ex- 60 tends through the rectangular hole 24 in an auxiliary jaw 25 having a serrated working face 26, the serrations of which fit into those of the working face 11.

The serrated working face 26 is slightly 65 inclined to the flat working face 27 on the opposite side of the auxiliary jaw 25.

Owing to the flat sides of the portion 13 fitting the hole 24 the auxiliary jaw 25 may move endwise of this portion 13, but is pre- 70 vented from all other movement relatively thereto.

The movable jaw 14 has a threaded socket 28 into which extends one end of the adjusting screw 29 provided with a milled turning 75 flange 30, the edge of which is positioned in a notch 31, thereby preventing any end movement of said screw 29.

The opposite end of the screw 29 is pro- 80 vided with a cone-shaped portion 32 revolu- bly mounted in a socket 33 in an end face of the member 17.

When the milled flange 30 is actuated to rotate the screw 29 the jaw 14 will be moved endwise of the portion 13, the direction of 85 movement depending upon the direction of rotation imparted to said screw.

The fixed jaw 10 is provided in one side face with a groove 34 and a similar groove 35 is formed in a side face of the movable 90 jaw 14, these detents 34, 35 being positioned opposite each other.

The auxiliary jaw 25 has a pivot pin 36 in one side extending through a spring clip 37 having at one end an inturned end 38 95 adapted to enter one of the grooves 34, 35 to lock said auxiliary jaw to either the fixed jaw 10 or the movable jaw 14 as desired.

When this inturned end 38 is in the groove or detent 34 the auxiliary jaw 25 is locked 100 to the fixed jaw 10 and the working faces 15, 27 are parallel.

When in this position the device may be used as an ordinary monkey wrench.

When the clip 37 is moved about its pivot 105 causing the inturned end 38 to engage the groove 35 the serrated working faces 11, 26 will be parallel and the device may be used as a pipe wrench.

Should the auxiliary jaw 25 become 110

broken or unduly worn it may be replaced by a new jaw by removing all the parts of the wrench from the shank 12.

This is accomplished by unscrewing the screws 19 and 23 and sliding all the parts endwise off the shank 12.

This makes a very simple and inexpensive construction of wrench which may be used either as a monkey wrench or pipe wrench, making it particularly desirable for home use.

Having described my invention, I claim:

1. In a wrench, a handle; two main jaws one immovable relatively to said handle and having its working face inclined and serrated, and the other movable relatively to said fixed jaw and having an unbroken working face always perpendicular to the axis of said handle; and an auxiliary jaw interposed between and slidable towards and from said main jaws and adapted to be locked to either, said auxiliary jaw being wedge shaped with an inclined working face serrated and opposed to the serrated face of the fixed jaw.

2. In a wrench, a handle; a shank secured thereto having formed integral therewith a main jaw with its working face inclined and serrated; another main jaw slidable lengthwise of said shank toward and from said fixed jaw with an unbroken working face perpendicular to its path of movement; an

auxiliary jaw disposed on said shank and slidable lengthwise thereof, said auxiliary jaw having an unbroken working face parallel with the working face of the movable main jaw and another working face serrated and parallel with the inclined working face of the fixed main jaw, the teeth of which fit the teeth on said auxiliary jaw when contacting therewith; and means for locking said auxiliary jaw to either main jaw.

3. In a wrench, a handle; a shank secured thereto having formed integral therewith a main jaw with its working face inclined and serrated; another main jaw surrounding said shank and slidable lengthwise thereof and provided with an unbroken working face perpendicular to its path of movement; an auxiliary jaw surrounding said shank and slidable lengthwise thereof, said auxiliary jaw being thicker at its outer end and having one unbroken working face parallel and opposed to the working face of the movable main jaw and an inclined serrated working face parallel to the serrated working face of the fixed jaw, the teeth of said serrated working faces being adapted to interlock when in contact; and means for locking the auxiliary jaw to either main jaw.

Signed by me at 746 Old South Bldg., Boston, Mass., this 20th day of March, 1926.

BERNARD McGILVRAY.
